US0D1068446S

(12) **United States Design Patent** (10) **Patent No.:** **US D1,068,446 S**
(45) **Date of Patent:** **** Apr. 1, 2025**

(54) **CAM LOCK**

(71) Applicant: **MCS Industries, Inc.**, Easton, PA (US)

(72) Inventors: **Michael Lee Pyle**, Sugar Grove, IL (US); **Steven Patrick McGowan**, Perkasie, PA (US); **Matthew Scott Kressin**, Allentown, PA (US); **Richard Joseph Ehrhardt**, Easton, PA (US); **Robert Terry Coyle, Jr.**, Palmer, PA (US)

(73) Assignee: **MCS Industries, Inc.**, Easton, PA (US)

(**) Term: **15 Years**

(21) Appl. No.: **29/767,260**

(22) Filed: **Jan. 21, 2021**

Related U.S. Application Data

(62) Division of application No. 29/637,961, filed on Feb. 23, 2018, now Pat. No. Des. 911,813.

(57) **CLAIM**

The ornamental design for a cam lock, as shown and described.

DESCRIPTION

FIG. 1 is a top front perspective view of a cam lock showing our new design;

FIG. 2 is a top rear perspective view thereof;

FIG. 3 is a bottom front perspective view thereof;

FIG. 4 is a bottom rear perspective view thereof;

FIG. 5 is a front view thereof;

FIG. 6 is a rear view thereof;

FIG. 7 is a left-side view thereof;

FIG. 8 is a right-side view thereof;

FIG. 9 is a top view thereof; and,

FIG. 10 is a bottom view thereof.

The broken lines illustrate portions of the cam lock that form no part of the claimed design.

1 Claim, 10 Drawing Sheets
